CLIP

James E. Petrie, Minneapolis, Minn., assignor to
 Petrie Specialties Co., Minneapolis, Minn., a
 corporation of Minnesota

Application May 1, 1950, Serial No. 159,281

1 Claim. (Cl. 24—261)

1

My present invention relates to clips and more particularly to a photo-print clip.

The object of this invention is to provide a highly efficient clip for the handling of photo-prints during the processing thereof and for holding the same suspended from a support while drying after processing.

To the above end the invention consists of the novel construction and arrangement hereinafter described and defined in the claim.

In the accompanying drawing, which illustrates the invention, like characters indicate like parts throughout the several views.

Referring to the drawing:

Fig. 1 is a perspective view of the improved clip approximately double the actual size.

Fig. 2 is a front elevational view of the same.

Fig. 3 is a side elevational view of the improved clip.

Fig. 4 is a plan view of the top portion of the improved clip, and

Fig. 5 is a view corresponding to Fig. 2 with the exception that the clip is open.

The improved clip 6 is formed of a single piece of spring wire folded, at its intermediate portion upon itself, to form an open eye 7. This eye 7 is in the form of an inverted V, the legs of which are designated by the numerals 8 and 9. The wire at the lower ends of the legs 8 and 9 is bent outwardly in opposite directions from the plane of the eye 7 to form a pair of short parallel spacing members 10 and 11 respectively. At the outer end of the spacing member 11, the wire is bent horizontally parallel to the plane of the eye 7 and affords a closure member 12 for said eye, except for a passageway 13 between the closure member 12 and the leg 8.

The wire at the outer end of the spacing member 10 and also at the outer end of the closure 12, is first bent downwardly, then upwardly and again downwardly to form a pair of hooks 14. These hooks 14 are laterally spaced apart parallel to the eye 7 and are located, one on each side thereof. The body members 15 of the hooks 14 extend below the outer members of said hooks.

The wire at the lower ends of the hook body members 15 is bent inwardly to afford a pair of horizontal overlapping members 17 and 18, respectively. The length of the members 17 and 18 corresponds approximately to the distance between the hook body members 15.

The wire at the outer ends of the members 17 and 18 is bent downwardly and inwardly to afford a pair of jaws 19 and 20, respectively. At the lower end of the jaw 19, the wire is bent

5 to form an eye 21, and then turned upwardly at 22. The jaw 20, at its lower end portion, is bent to form a pin 23 that when the jaws 19 and 20 are closed, extends through the eye 21.

10 The improved clip 6 may be attached to a photo-print, not shown, by first opening the jaws 19 and 20 to withdraw the pin 23 out of the eye 21. Next, the clip 6 is moved to insert the photo-print edgewise between the eye 21 and the end of the pin 23. When the finger pressure on the jaws 19 and 20 is released, said jaws will close and pinch the photo-print between the eye 21 and the end of the pin 23. If desirable, the pin 21 may be forced to puncture the margin of the photo-print so that the same will hang therefrom, simply by applying pressure to the jaws 19 and 20 to force the same toward each other. Obviously, the clip will also hold a photo-print without puncturing the same, by spring pressure of the jaws 19 and 20 on either side of said photo-print.

15 The improved clip may be hung from a support by its eye 7 or may be hung on a line by means of its hooks 14. The clip may also be hung from a line extending through the eye 7. To thus apply the clip to a line, the jaws 19 and 20 are opened to receive the line between the eye 21 and the pin 23 permitting the line to enter the eye 7 through the passageway 13.

20 From the foregoing description, it is evident that a photo-print may be handled by means of the improved clip without touching the print with the bare hands.

25 The drawings illustrate a commercial form of the invention, but it will be understood that the same is capable of certain modifications as to the details of construction, arrangement and combination of parts, within the scope of the invention herein disclosed.

30 What I claim is:

35 A clip of the class described formed of a single piece of spring wire folded at its intermediate portion upon itself to provide an open eye in the form of an inverted V having diverging legs, said wire at the lower ends of the legs, being bent laterally outwardly in opposite directions from the plane of the eye to provide a pair of spacing members, the wire at the outer end of one of the spacing members being bent horizontally parallel to the plane of the eye to afford a closure member for the eye except for a passageway between the outer end of the closure member and the adjacent leg of the eye, the wire at the outer end of the spacing member and the outer end of the closure member being

bent to form a pair of laterally spaced hooks in which the wire first extends downwardly, thence upwardly, and again downwardly to form the body members of the hooks, the wire at the lower ends of the body members being bent horizontally inwardly into overlapping arrangement, and thence down into converging relation to afford a pair of normally closed jaws, one of said jaws terminating in an eye and the other terminating in a pin normally extending through the eye, the wire from the eye being extended upwardly to the upper ends of the jaws.

JAMES E. PETRIE.
